UNITED STATES PATENT OFFICE

SIGMUND GUGGENHEIM, OF BERLIN-WILMERSDORF, GERMANY.

ELECTRIC FURNACE.

1,157,691.

Specification for Design.

Patented Oct. 26, 1915.

Application filed February 18, 1914. Serial No. 819,341.

To all whom it may concern:

Be it known that I, SIGMUND GUGGENHEIM, a citizen of the Republic of Switzerland, residing at Berlin-Wilmersdorf, Germany, have invented a new and useful Improvement in Electric Furnaces Operated by Eddy-Currents, of which the following is a specification.

My invention relates to an electric furnace in which the material operated upon, which may be a metal, metallic ore or other suitable substance becomes the seat of eddy currents which are produced in said material by a suitable arrangement of fluctuating magnetic circuits.

In an application for a patent filed in Germany, September 30, 1912, I have described an electric furnace of the character thus referred to. In said furnace I place the material to be melted in a suitable receptacle and then arrange said receptacle so that it is located in the air gap of two or more electro-magnetic circuits. These circuits may be energized by connecting them to any suitable alternating current network. By thus providing two or more magnetic circuits, the lines of force respectively due thereto will mutually influence one another so as to pass to a very considerable degree through the body of the material to be melted in which there is thereby established what may be termed eddy current centers. A large amount of energy is in this way injected into the material as contrasted with the amount possible where only one magnetic circuit (one air gap) is employed, for in this latter case but few of the lines get much within the surface (skin effect). A large amount of energy is in this way injected into the materials.

It is the object of this, my present invention, to improve the arrangement thus referred to and as described in my German application, by enabling a still greater introduction and concentration of magnetic lines to be effected in the body of the material, thereby making the melting operation still more economical.

More specifically it is the object of my invention to provide an arrangement comprising three separate magnetic circuits connected respectively in the three individual conductors of a three phase alternating circuit, or, as it is often called, rotary circuit. The windings of the separate magnets are suitably so arranged, as regards one an-

other, that the magnetic phases do not agree with the current phases. Or, a plurality of groups of three circuits as a base may be used within the spirit of the invention.

My invention will be better understood by referring to the drawing, in which—

Figure 1 shows, diagrammatically, both the current and the magnetic phases in a three phase circuit, when the magnets are similarly wound and connected; Fig. 2 is a view similar to Fig. 1 showing the magnetic phases when the magnets are similarly wound, but one is reversely connected as regards the others; Fig. 3 represents, diagrammatically in side elevation, a furnace provided with three magnetic circuits according to my invention; Fig. 4 shows the furnace of Fig. 3 in plan, and Fig. 5 is a plan view from below of the furnace of Fig. 3 showing the windings and connections of the magnets and there is shown in addition a special phase displacing arrangement on one of said magnet windings.

In the drawings the material *a* to be heated or melted is contained in a receptacle *b* in the air gap between pole pieces *c'* and *d'*, *c²* and *d²* and *c³* and *d³* of the three magnetic circuits 1, 2 and 3, energized respectively by similar windings *e'*, *e²* and *e³*. Let windings be connected in the usual way in the individual conductors of a suitable three phase circuit.

When the several windings of the several magnetic circuits are all arranged in the same sense, and connected as above, so that their current supply flows in the same sense, a very considerable proportion of the magnetic lines of force generated in a given magnet will not pass entirely through the material to be melted from pole to pole, but, starting from the several poles successively, for example from pole *c³*, will bridge across to the neighboring poles *c'*, *c²*; starting from pole *d³* the magnetic lines will in the same proportion go to poles *d'*, *d²*, etc.; as a consequence the body to be heated fails to receive a considerable proportion of the energy intended for it. If, however, in connecting the several magnetic circuits, the windings of one of them be reversed, as regards those of the other two circuits, as is indicated diagrammatically in Fig. 5, where two of the windings *e'* and *e²* are joined in the same sense, but oppositely from that of *e³*, then the magnetic phase of circuit 3 will be displaced 180° from normal. That is to

say the three magnetic phases will be 60° apart, as indicated in Fig. 2, instead of 120° apart, as indicated in Fig. 1. By this arrangement a much larger number of lines of force will go through the material from one pole of a given circuit to the other, than is the case when the phases are 120° apart, as indicated in Fig. 1. Besides, or instead of having the windings of one magnet circuit reversed, as regards those of the other two, I may, if I prefer, insert an inductive or ohmic resistance in one of said circuits, or different inductive or ohmic resistances in different circuits. Or, instead of having the three magnetic circuits similarly wound and differently connected, I may have them differently wound, but similarly connected. Furthermore, I am not confined to connecting my several magnetic circuits with a three phase circuit, but may, if I desire, connect the circuits with any suitable alternating current network. The only requirement is that the magnetic circuits be so arranged that the magnetic phases be unequally rather than equally displaced.

Having described my invention, I claim:

1. An electric furnace comprising, in combination, three electromagnets each provided with an air gap, a receptacle located so as to be in each of said gaps, and windings upon said magnets adapted to be so

energized by the phase of a polyphase current that some of the magnetic phases will be unequally displaced.

2. An electric furnace comprising, in combination, three electromagnets each provided with an air gap, a receptacle located so as to be in each of said gaps and identical windings upon each of said magnets one of said windings being reversely arranged, however, as regards those of the other two magnets, said windings being adapted to be respectively, normally connected in the respective conductors of a three phase alternating network so that the magnetic phases are different from the electrical phases.

3. An electric furnace comprising, in combination, three electromagnets each provided with an air gap, a receptacle located so as to be in each of said gaps and windings upon said magnets, said windings having different characteristics so that when energized by a three phase alternating current network the magnetic phases will be unequally displaced.

In testimony whereof I have hereunto set my hand in the presence of two subscribing witnesses.

SIGMUND GUGGENHEIM.
